REFRIGERATING APPARATUS

Hugh J. Scullen, Detroit, Mich., assignor to Nash-Kelvinator Corporation, Detroit, Mich., a corporation of Maryland

Application September 18, 1943, Serial No. 502,107

1 Claim. (Cl. 62—125)

This invention relates to refrigerating apparatus, and more particularly to refrigerating apparatus of the multiple temperature type.

One of the objects of my invention is to provide a new and improved arrangement for freezing substances, and for cooling circulating air in a refrigerator cabinet so as to maintain a relatively high humidity within the cabinet.

Another object of my invention is to provide an improved refrigerating apparatus comprising an insulated cabinet divided into a freezing compartment and a food compartment, in the former of which is disposed a primary refrigerant evaporating element for freezing ice cubes and the like, and in the latter of which are disposed a plurality of secondary refrigerant evaporating elements for cooling the circulating air.

A further object of my invention is to provide an improved refrigerating apparatus comprising a primary refrigerating system having a high side and a low side for freezing large quantities of ice cubes and the like, and a secondary refrigerating system having a plurality of high temperature refrigerant evaporating elements for cooling circulating air in the food compartment of the cabinet, said evaporating elements being operatively interconnected by a plurality of refrigerant conveying conduits which are placed in heat exchange relation with a portion of the low side of the primary system.

Another object of my invention is to provide an improved arrangement for the ready removability of the aforesaid primary refrigerating system as a unitary structure without disturbing the secondary system.

Further objects and advantages of the present invention will be apparent from the following description, reference being had to the accompanying drawing, wherein a preferred form of the present invention is clearly shown.

In the drawing:

Fig. 1 is a front vertical view partly in elevation and partly in cross section of a refrigerating apparatus embodying features of my invention;

Fig. 2 is a side vertical view in cross section of the apparatus shown in Fig. 1;

Fig. 3 is a perspective view of a portion of the apparatus shown in Fig. 1; and

Fig. 4 is a cross sectional view of another portion of the apparatus shown in Fig. 1.

Referring to the drawing, the numeral 20 designates, in general, a cabinet having a compartment 22 for the storage of foods to be refrigerated and a low temperature or freezing

compartment 23 located within the compartment 22 near the top and midway between the walls thereof. The cabinet is also provided with a machine compartment 24 located below the food compartment 22. Compartment 22 is provided with an opening closed by a door 26, while compartment 23 is also provided with an opening closed by a door 28. The walls of the cabinet enclosing the food compartment 22 are insulated and include side walls 30, rear wall 31, bottom wall 32 and top wall 33. An inner metallic lining member 34 forms the inner walls of the food compartment and is preferably provided with a coating of vitreous enamel, such as porcelain, to provide a neat appearing compartment and one which may easily be cleaned. The food compartment 22 and freezing compartment 23 are separated by a U-shaped partition member 35 which is preferably composed of a high heat conductive material, such as sheet metal, but which may consist of insulating material, if desired. This partition is secured to the top wall 33 and rear wall 31. The machine compartment 24 has an opening at the front of the cabinet 25 which is closed by a movable door 36 to afford ready access to said compartment. A vegetable bin 38 is attached to the inside of the door 36. The entire cabinet is raised above the level of the floor by means of legs 40 to allow air from the room to circulate freely through an opening 41 into the machine compartment and out through an opening 42 at the rear of the compartment.

Numeral 45 designates, in general, a primary refrigerating system which includes a refrigerant cooling or evaporating element 46 disposed in the freezing compartment 23 and a refrigerant condensing or circulating element 47 disposed in the machine compartment 24. These elements are operatively associated with one another by a small diameter tube 48 and a vapor return conduit 50. The entire primary refrigerating system is adapted to be removed as a unit whenever desired, as will be described below.

The evaporating element 46 comprises, in general, two horizontal sections of serpentine refrigerant conveying conduits, designated by the numerals 52 and 54, respectively. These sections are supported by a sheet metal box-like casing 56 which is provided with a number of shelves 57 and with an opening 58 at the front thereof. This casing is rigidly secured at the rear by suitable means to a removable section 59 of the insulated wall 31. Section 52 is directly secured by any suitable means to the bot-

tom of the casing while section 54 is directly secured in a similar manner to one of the shelves 57. A conduit 60 connects the two sections in series. The small diameter tube 49 is connected to the lower section 52 while section 54 is connected to an accumulator 61, preferably by a conduit 62. Vapor return conduit 58 connects the accumulator with the condensing unit.

The refrigerant condensing element 47 comprises, in general, a motor compressor unit 65 and a condenser 66. The motor compressor unit is of the type which includes a compressor and motor directly connected and enclosed within a hermetically sealed casing. Units of this type are well known in the art and further illustration thereof in the drawing is deemed unnecessary. The cooling of the condensing element may be accomplished either by forced or natural convection, the latter being the one illustrated. Air from the room circulates through the opening 41 over the condensing unit and out through the opening 42 at the rear of the machine compartment. A flue, not shown, may be provided on the rear wall of the cabinet for enhancing the natural convection effect as is well known in the art.

In operation, the compressor withdraws evaporated refrigerant from the evaporating element through the vapor conduit 50, compresses the gaseous refrigerant and delivers it to the condenser 66 wherein it is liquefied and from which it is delivered in liquid form to the evaporator 46 through the small diameter tube 49. This tube is of proper dimensions to meter the quantity of liquid refrigerant flowing from the condensing element to the evaporating element during entire operation of the system. The charge of refrigerant in the system is preferably such that liquid refrigerant is supplied in sufficient quantities to the evaporator 46 so that during normal operation of the system some liquid refrigerant reaches the accumulating element 61. The vapor return conduit 58 connecting the accumulating element with the condensing unit is preferably arranged in intimate heat exchange relation with the small diameter tube 49. The compressor is preferably controlled to operate intermittently in accordance with the temperature conditions within the refrigerator cabinet by a heat responsive switch in the usual manner. The temperature of the evaporating element 46 is maintained at a value sufficiently low to effect rapid freezing of ice cubes and the like, and also to maintain freezing temperatures throughout the freezing compartment. A metallic sleeve like member 68 is provided for storing frozen foods below the casing 55. A resilient sealing member 69 is disposed between the casing 55 and the front edges of the casing 55 and sleeve member 68 to prevent circulation of air between the interior of the refrigerator and the walls thereof.

Numeral 70 designates, in general, a secondary refrigerating system which is adapted to maintain the food compartment 22 at a relatively high and uniform refrigerating temperature and at a relatively high humidity so that little dehydration of the foods stored therein is accomplished. The secondary refrigerating system includes a pair of evaporating elements designated, in general, by the numerals 72 and 74 and a pair of interconnecting refrigerant conveying conduits, designated by the numerals 76 and 78. The evaporating elements 72 and 74 are alike in construction and preferably consist of refrigerant carrying serpentine conduits 76 and 78, respectively, ar-

ranged in a vertical plane and provided with vertically extending fins 81 and 82, respectively, which are secured to the serpentine conduits in intimate heat exchange relation. The evaporating elements are disposed on opposite sides of the freezing compartment adjacent the rear wall of the food compartment and are secured to the rear wall. They are connected by the refrigerant conveying conduits 76 and 78. Conduit 78 connects the top of element 72 with the bottom of element 74 while conduit 76 connects the top of element 74 with the bottom of element 72. These connecting conduits 76 and 78 are arranged so that intermediate portions 83 and 84, respectively, thereof lie in a horizontal plane parallel to each other at or above the level of the topmost part of the evaporating elements. It is these portions which serve as condensing elements of the secondary system by being placed in heat exchange relation with the cylindrical accumulating element 61 of the primary system. The portions 83 and 84 are firmly secured as by soldering to a split sheet metal cylindrical clamping element 85 which is adapted to be removably secured in direct contact therewith to the accumulating element by means of bolts 86.

In operation, refrigerant evaporated in the cooling element 72 circulates through the condensing portion 84 of conduit 78 into heat exchange relation with the accumulator where it is condensed. It is then delivered as a liquid to the bottom of cooling element 74. The liquid circulates upwardly through the latter and is converted at least partially into a gas. The resulting mixture is conveyed by conduit 76 through the condensing portion 83 into heat exchange relation with the accumulator where condensation of evaporated refrigerant takes place. The liquefied refrigerant is then delivered to the evaporating element 72. The temperature differential maintained between the primary evaporator and the secondary evaporators may be controlled by adjusting the rate of heat exchange between the accumulator 61 and the cylindrical clamping member 85. Preferably, the temperature of the secondary evaporating elements 72 and 74, that is, on the surface of the fins, is maintained above freezing most of the time so that frost does not form permanently thereon. Any moisture which collects on the cooling elements 72 and 74 may be drained into pans (not shown). A pan 88 is provided below the freezing compartment for collecting any water formed on the outside surface of the partition 35.

The entire primary refrigerating system may be removed from the cabinet as a unitary structure. The structure includes the condensing element 47, the evaporating element 46, the liquid accumulator 61 and the removable insulating member 58. The small diameter tube 49 and vapor return conduit 58 both extend to the evaporator from the condensing unit through the insulating member 58. A recess is provided in the insulating member for the accumulator and the interconnecting conduits 76 and 78. To remove the primary system, it is only necessary to release the clamping element 85. Then the entire primary structure may be drawn rearward from the cabinet, the evaporator sliding through the opening at the rear of the freezing compartment and the condenser sliding out the rear of the machine compartment.

Although only a preferred form of the invention has been illustrated, and that form de-

scribed in detail, it will be apparent to those skilled in the art that various modifications may be made therein without departing from the spirit of the invention or from the scope of the appended claim.

I claim:

Refrigerating apparatus comprising a cabinet having inner and outer casings, insulation between said casings, said inner casing forming a food storage compartment, a partitioning casing positioned in said inner casing to form a freezing zone, a refrigerant evaporating element positioned within the confines of said partitioning casing and including an accumulator of cylindrical formation positioned outside of said par-

5 titioning casing and at the rear thereof and in a pocket formed in said insulation, and a secondary refrigerating system including a removable clamping member surrounding said accumulator, a secondary condenser in contact with said clamping member and two sections of refrigerant evaporating elements one of which is positioned in the food storage compartment between one side of the inner casing and said partitioning casing and the other section is positioned in said food storage compartment between the opposite side of said inner casing and said partitioning casing.

HUGH J. SCULLEN.
